Attorney.

UNITED STATES PATENT OFFICE.

JOSEPH J. SHICKLUNA, OF BUFFALO, NEW YORK.

POLISHING MOP.

Application filed April 5, 1920. Serial No. 371,237.

To all whom it may concern:

Be it known that I, JOSEPH J. SHICKLUNA, a citizen of the United States, residing at Buffalo, in the county of Erie 5 and State of New York, have invented certain new and useful Improvements in Polishing Mops, of which the following is a specification.

My invention relates to improvements in 10 mops, and more particularly to that type of mops known as "polishing mops" and having a swab portion adapted to be saturated with a liquid polish for polishing finished hard wood floors and the like.

15 The primary object of my invention is to provide an improved device of this kind, which will permit of readily removing the swab from the mop head when it is desired to wash or otherwise cleanse the same, 20 and to as readily apply the swab to the mop head.

A further object of my invention is to provide a mop head and an improved swab having a pocket into which the mop head 25 is to be inserted, with co-acting means on both for fastening the two together.

A still further object of my invention is to provide an improved swab having a mop head enclosing-portion and a mass 30 of fibrous strands or yarns applied to said enclosing portion.

With these and other objects in view, the invention consists in the novel features of construction and in the arrangement and 35 combination of parts to be hereinafter described and more particularly pointed out in the subjoined claims.

In the drawings:—

Fig. 1 is a perspective view of a complete 40 polishing mop constructed in accordance with my invention; the handle, however, being broken for the purpose of saving space on the drawings.

Fig. 2 is a sectional elevation of the lower 45 end of the polishing mop, the swab being shown in section as applied to the mop head.

Fig. 3 is a perspective view of the swab showing the enclosing or enveloping portion partly open to form a pocket for the 50 insertion of the mop head thereinto.

Fig. 4 is a perspective view of the swab showing the enclosing or enveloping portion opened full, thus enabling the swab 55 to be thoroughly washed or otherwise cleansed.

Fig. 5 is a horizontal section taken on line 5—5, Fig. 2, with the swab removed from the mop head.

The device comprises a mop head 1, a 60 swab 2, a connector-fitting 3 pivotally attached to the mop head, and a handle 4.

The mop head is preferably cast but may be otherwise formed, either into triangular shape or otherwise. It is, however, preferably of triangular shape and has two forwardly converging side or bounding members 5 and a transverse rear or bounding member 6; said members being connected together at the angles of the triangle, preferably by rounded portions 7.

Within the space formed by the bounding members 5 and 6, transverse connector members 8 are arranged, said members connecting the converging side members 5. 75 Connecting two of said transverse members 8 is a bridge portion 9 forming a pivot-receiving lug provided with a central opening or hole 10.

The bounding members 5 and 6 and the 80 parallel transverse connector members 8 are comparatively slender and the mop head may therefore be referred to as of the skeleton type; that is a mop head formed of slender connected members separated at 85 least in part by comparatively large spaces.

The fitting 3 is cast, stamped, or otherwise constructed in the form of a socket 11 at its upper or outer end, into which the lower end of the handle 4 is inserted and 90 clamped in any approved manner. This fitting is bifurcated at its lower or inner end to form two spaced yielding clamping members 12, 13. Between each of these

clamping members and the pivot-receiving 95 lug 9 are arranged friction washers in sets of three, each set comprising two fiber or similar washers 14 and a metal washer 15, the holes of which are alined with the hole 10 of the pivot-receiving lug, the fiber or similar washers of each set lying, respectively, in contact with said pivot-receiving lug 9 and the inner face of the co-operating clamping member 12 or 13, as the case may be, with the metal washer 15 between 100 the two.

Extending through the central opening or hole 10 in the pivot-receiving lug 9 and the holes in the friction washers is a bushing 35.

The clamping member 13 has an axial bolt 110 hole 16 with its outer portion countersunk and the clamping member 12 has an axial

opening 17 serving as a bolt hole and being flared outwardly.

Passing through the bolt holes in the clamping members and through the bushing 35 is a screw bolt 18 having an outwardly flared head at one end fitting into the countersunk portion of the bolt hole 16. Said screw bolt serves as a pivot and has the usual transverse kerf 19 and the countersunk portion of said bolt hole 16 has an inwardly-directed lip 20 fitting into the kerf of said bolt head at one end thereof, as best shown in Fig. 2. By the use of the bushing 35, the threads of the screw-bolt 18 cannot come in contact with the friction washers and said washers are kept in proper position when withdrawing the screw bolt.

Threaded onto the screw bolt at the opposite end thereof is a clamping nut 21 having an inwardly-projecting conical portion 22 adapted to have the outwardly-flaring opening or bolt hole 17 in the clamping member 12. With the parts constructed as described, the screw bolt is prevented from turning, and when tightening the nut 21, friction is created between the same and the wall of the bolt hole 17 to prevent loosening of said nut. The tightening of the nut also tends to draw the clamping members 12, 13 of the connector-fitting toward each other so as to create friction between the friction washers and the parts in contact therewith.

Projecting inwardly at an angle from the rounded portions 7 at the rear of the mop head are retainer prongs 23, said prongs being therefore at an angle to each other, and directed forwardly from the rear bounding member 6 midway between its ends is a third retaining prong 24, each prong having its extremity curved upwardly and pointed, as at 25, Fig. 2.

The swab 2 is formed of a mass of fibrous strands or yarns 26 sewed or otherwise fastened to a canvas or similar flat member 27 having substantially the shape of the mop head and having at opposite sides flaps 28 adapted to overlie the flat portion, as shown in Fig. 3. These flaps may overlap, or abut as shown in Fig. 3, when folded, and along their marginal portions eyelets 29 are formed through which suitable lacing 30 is passed with the ends thereof tied, as at 31. Each of these side flaps has an eyelet 37 near its rear end, for a purpose to presently appear. At the rear of the flat portion 25 is a flap 33 adapted to be folded forwardly over the flat portion 25 and this rear flap has eyelets 34 formed therein adapted to receive the pointed ends of the retainer prongs 23, 24 at the rear of the mop head, as clearly shown in Figs. 1 and 2.

With the flaps of the swab arranged as shown in Fig. 3, a pocket 34 is formed in the top of the swab, and in this pocket the triangular mop head may be inserted. Af-

ter the mop head is positioned within the pocket, the two retainer prongs 23 are entered in the eyelets 32 in the side flaps 28; the rear flap 30 is then folded over the rear of the mop head and the two end eyelets in said flap brought into registration with the eyelets 33 in the side flaps, thus enabling the pointed extremities of the angular prongs 21 to be entered through said last-mentioned eyelets while the intermediate eyelet of said rear flap receives the pointed extremity of the forwardly-directed prongs 24. The mop then has the appearance shown in Fig. 1, with all of the mop head fully concealed, excepting the bolt receiving lug 9 and the extremities of the prongs 21, 22.

By directing the retainer prongs 23, 24 in different directions, they serve as means to prevent accidental disconnection of the swab from the mop head, due to the counteracting pulling and pushing strains to which the swab is subjected during the manipulation of the mop.

Having thus described my invention, what I claim is:—

1. A mop of the kind described comprising a flat mop head having pointed retainer prongs extending upwardly at its rear end, a swab having a pocket portion to receive said mop head and a flap at its rear end folded onto said mop head and provided with eyelets through which the prongs of said mop head are passed.

2. A mop of the kind described comprising a flat mop head having forwardly and upwardly-directed prongs at its rear end and a forwardly-directed prong between said first-mentioned prongs, a swab having a flat pocket portion and a mass of fibrous strands or yarns applied to the upper side of said pocket portion, said pocket portion having also a flap at its rear end folded over the rear portion of said mop head and provided with eyelets adapted to receive said prongs.

3. A mop of the kind described comprising a triangular flat mop head having forwardly-converging side members connected together at their front ends and a rear transverse member connected to the rear ends of said side members, forwardly and inwardly directed prongs at the points of connection of said side members with said rear transverse member, a forwardly-directed prong on said rear transverse member between said first-mentioned prongs, and a triangular shaped envelope enclosing said mop head and having an opening through which said mop head is passed, a flap at the rear end of said envelope having eyelets adapted to receive the prongs at the rear of said mop head and a mass of fibrous strands or yarns secured to its under side.

4. A mop of the kind described, comprising a triangular open frame formed of forwardly converging side members and a rear

cross member connecting the rear ends of said side members, said frame having a pair of transverse connecting members between said rear cross member and the apex of the triangle, and an upstanding lug bridging the space between said transverse members, a handle attached to said upstanding lug and a swab provided with a triangular pocket into which said triangular open frame is inserted.

5. A mop of the kind described, comprising a triangular open frame having forwardly converging side members and a rear connecting member connected to the rear ends of said side members, diagonally-disposed prongs extending inwardly from the points of connection of said side members to

said rear cross member, and a forwardly-directed prong extending from said rear cross member between said first-mentioned prongs, said frame having also a pair of transverse spaced members forward of said prongs and an upstanding lug bridging the space between said transverse members, a handle connected to said lugs, and a swab having a triangular pocket adapted to receive said triangular frame and a flap at its rear end adapted to fold over the rear portion of said frame, said flap being provided with openings through which said prongs are passed.

In testimony whereof I affix my signature.

JOSEPH J. SHICKLUNA.
